WHEEL BALANCING UNIT

Wilbur C. Rexroat, Atlanta, Ga.

Application August 1, 1955, Serial No. 37,255

Term of patent 14 years

(Cl. D55—1)

FIG. 1

FIG. 2

FIG. 3

Fig. 1 is a front elevation of a wheel balancing unit showing my new design.

Fig. 2 is a right side view of the device shown in Fig. 1.

Fig. 3 is a top plan view of the device shown in Fig. 1.

The essential features of my design reside in the portions shown in full lines.

I claim:

The ornamental design for a wheel balancing unit, substantially as shown and described.
